UNITED STATES PATENT OFFICE.

JOHN M. BRUNS, OF WATERLOO, IOWA, ASSIGNOR TO WATERLOO CEMENT MACHINERY CORPORATION, OF WATERLOO, IOWA.

ACTUATING MEANS FOR DUMPING CONCRETE-MIXERS.

1,140,298.

Specification of Letters Patent.

Patented May 18, 1915.

Application filed February 14, 1910. Serial No. 543,865.

To all whom it may concern:

Be it known that I, JOHN M. BRUNS, a citizen of the United States of America, residing at Waterloo, in the county of Black Hawk and State of Iowa, have invented certain new and useful Improvements in Actuating Means for Dumping Concrete-Mixers, of which the following is a description.

10 In rotary concrete mixers and like mechanisms of certain types, it is necessary after the mix has been properly prepared to dump or tilt the mixing chamber so as to discharge the contents thereof, after which the chamber is returned to its normal operating position. My invention is adapted for use on devices of this kind and is shown as applied to a rotary concrete mixer of well known form, it being understood that it may be 15 used wherever found applicable.

20 My invention has among its objects the production of a simple, satisfactory and efficient device of the kind described that may be manufactured at comparatively small cost.

25 It is designed to accomplish the discharging operation with the minimum power and the same consists of the novel construction, arrangement and combination of parts hereinafter shown and described and more particularly pointed out in the claims.

30 In the drawings wherein like reference characters indicate like or corresponding parts, Figure 1 is a partial side elevation of a concrete mixer equipped with my improved device, Fig. 2 is a front view of the same showing the parts in their normal operating position, Fig. 3 is a similar view showing the mixing chamber tilted to discharge its contents, Fig. 4 is a detail view of the preferred form of lever used, Fig. 5 is a fragmentary view showing the preferred means of adjusting the position of the pivotal point at which the lever is connected to the supporting frame of the chamber, Fig. 6 is a sectional view substantially on line 6—6 of Fig. 5, Fig. 7 is a side view illustrating the manner of connecting the lower end of the preferred form of lever to a fixed part of the supporting frame, Fig. 8 is a section substantially on line 8—8 of Fig. 7, and Fig. 9 is a side elevation of a

device showing a modification of the operating lever.

In the drawings, 1 is a supporting frame or standard.

5 2 is a main supporting frame for the mixing chamber, pivotally connected to the frame 1 at 3.

4 4 is the mixing chamber provided with a circumferential cog ring 5 which is engaged with and operated by driving gears (not shown) in the usual well known manner, to rotate the chamber.

6 6 is the receiving hopper and 7 the discharge spout.

As shown, the whole device is mounted upon a suitably formed truck 8 for convenience in transportation.

70 As shown in Figs. 1 to 8 inclusive, the operating lever 9 is pivotally connected to the frame or standard 1 as at 10, which serves as the fulcrum, and is also pivotally connected to the horizontal frame 2 as at 11. The said lever is provided with a longitudinal slot 12 which is extended at its lower end at substantially a right angle on the upper side of the lever so that when the chamber is in its operative position, as shown in Fig. 1, the pivotal stud 10 is positioned in said slot as indicated, the lever being preferably so formed that gravity is sufficient to engage the parts as illustrated, and thus lock them in position to prevent accidental disengagement. The upper part 80 of the lever, as at 14, may be of lighter material and detachable from the main lever 9.

75 In operation the operator seizes the lever 14 and in the initial movement of pressing 90 the same down lifts the lower end of the lever 9 moving the pivotal stud 10 out of engagement with the extension and in line with the longitudinal slot 12 and contacting with the lower side of said slot. Further 95 pressure causes the operating chamber to tilt upon its pivotal center 3, and as the frame 2 carrying the lever 9 moves downward it also carries the lever 9 with it, causing the pivot 11 to move toward the fulcrum point 100 10, the slot 12 permitting such an action. The result of this action is to move the weight point 11 toward the fulcrum point 10, reducing the distance between the two

and greatly increasing the leverage. This is important in view of the fact that the initial movement requires comparatively little power while as the chamber tilts it requires more power until finally the mix moves toward the discharge spout 7 by force of gravity and is discharged through said spout 7, substantially as shown in Fig. 3. After this is done the reverse action causes the parts to assume the normal operative position shown in Fig. 1.

In order to secure the reliable locking of the parts in operative position as explained, at the moment the frame 2 is substantially in horizontal position to secure the most satisfactory operation of the device, care is necessary to fix the position of the pivotal point 11. This point may be in the form of a stud, or as shown, may be secured by a suitable bolt passing through the side of the frame 2. This will require the boring of a suitable hole for said bolt after the parts have been trued up and the point exactly fixed. As a means for simplifying this operation means may be employed for securing an adjustment of this pivot, the means preferred being clearly shown in Figs. 5 and 6. As here shown, the frame 2 as made is provided with bolt holes for the receipt of bolts 15—15, and a plate 16 is provided having bolt holes therein constructed to register with the same. The plate is formed with a boss 17 offset from the center of the plate and having formed therein a suitable bolt hole to receive the bolt 18, which extends through the lever 9 as shown. By disengaging the bolts 15 the plate 16 may be turned a quarter or more, which will to the extent named adjust the distance between the pivotal bolt 18, corresponding to the pivotal point 11 shown in Fig. 1, and the pivotal point 10 engaging the lower end of the lever. In shop practice this is found to be a convenient means for constructing the parts so that they may be readily assembled without the necessary expense and time of measuring the distance between the two pivotal points and later boring a hole for the pivotal bolt.

As shown in Fig. 9, the reverse construction is illustrated in which the lower end of the lever is pivotally engaged with the pivot 10 by a suitable bolt passing through a corresponding hole in the end of the lever and the slot 12 is formed in the upper part of the lever with the pivot 11 engaged therewith. The right angular extension of the slot 12 is formed at the upper end of the slot and on the lower side thereof, while a spring 20 or equivalent means engaging the lever at one end and a fixed part of the device at the other, as shown, tends to normally hold the lever in its highest position, as shown in Fig. 9, to engage the pivot 11 with the transverse extension of said slot,

thus locking the parts together temporarily as before. The initial movement of the lever 14 detaches the pivot 11 from said notch, the pivot 10 acting as the fulcrum. The weight pivot 11 moves along the slot 12 toward the pivot 10, the weight and fulcrum being relatively brought nearer to each other as the operation proceeds as before and with the same effect.

It is obvious that after having described my invention various modifications may be made without departing from the spirit thereof, and hence I do not desire to be understood as limiting myself to the exact device in which my improvement is shown or the details and parts thereof as illustrated.

What I claim as new and desire to secure by Letters Patent is:

1. In a device of the kind described and in combination, a supporting frame, a tiltable member pivotally supported on a substantially horizontal line on the supporting frame, and means for moving said tiltable member, said means consisting of a lever having at one end a sliding pivotal connection with the supporting frame, and at a point intermediate of its ends also pivotally connected to the tilting member, said lever being provided with a longitudinal slot in which one of said pivots is positioned, and the other pivot being in fixed relation to the lever regarding movement longitudinally of the lever, whereby upon operating the lever the fulcrum and weight are caused to approach each other to modify the operative power required.

2. In a device of the kind described, and in combination, a supporting frame, a member pivotally supported in said frame for tilting movement about a horizontal axis and means for tilting said member comprising a lever having a connection at one end with the supporting frame at a point below the pivotal connection of the tiltable member with the supporting frame, and said lever also having a connection with the tilting member below the pivotal connection of the tilting member with the frame, both of said lever connections being positioned at the same side of a vertical plane passing through the pivot of the tilting member, one of said lever connections being a pivotal sliding connection, and the other of said lever connections being a fixed pivotal connection, whereby upon operating the lever the fulcrum and weight are caused to approach each other to modify the operative power required.

3. In a device of the kind described and in combination, a supporting frame, a tiltable member pivotally supported on a substantially horizontal line on the supporting frame, and means for moving said tiltable member, said means consisting of a lever having at one end a sliding pivotal connec-

tion with the supporting frame, and at a point intermediate of its ends also pivotally connected to the tilting member, said lever being provided with a longitudinal slot in 5 which one of said pivots is positioned, said slot having an angular extension in line with the said pivot when the parts are in operative position, and the other pivot being fixed to the lever respecting movement of the 10 same longitudinally of the lever, whereby

upon operating the lever the fulcrum and weight are caused to approach each other to modify the operative power required.

In testimony whereof I have hereunto signed my name in the presence of two sub- 15 scribing witnesses.

JOHN M. BRUNS.
